UNITED STATES PATENT OFFICE.

WALTER WINSTANLEY PECK, OF MANCHESTER, ENGLAND.

COKE-OVEN.

974,423.

specification of Letters Patent.

Patented Nov. 1, 1910.

Application filed October 28, 1909. Serial No. 525,010.

To all whom it may concern:

Be it known that I, WALTER WINSTANLEY PECK, a British subject, residing at Manchester, county of Lancaster, England, have 5 invented certain new and useful Improvements in Coke-Ovens, of which the following is a specification.

This invention relates to by-product coke ovens of the regenerative type heated by gas 10 and is designed to provide for a better distribution of the gas and heating of the air for combustion purposes.

In carrying out the invention the flues for the heated products and for heating the air 15 are built as a single flue or passage beneath the ovens divided by thin partitions such as tiles, the combustion chamber and the air distributing chamber are built as a single flue or passage divided by tiles with air passages 20 at the sides or edges the gas conduit is formed of perforated pipes supported in the combustion chamber and air heating passages are formed in the crown of the oven.

The invention will be fully described with 25 reference to the accompanying drawings forming part of the specification.

Figure 1. is a longitudinal sectional elevation of a horizontal oven through the retorts partly on line $x-x$ and partly on line $x-y$, 30 Fig. 3. Fig. 2. is a longitudinal section of oven through the flues on line $y-y$ Fig. 3. Fig. 3. is a transverse sectional elevation. Fig. 4. is a front elevation of oven. Fig. 5. is a 35 sectional detail of air and combustion chambers and gas conduit D. Fig. 6. is a longitudinal sectional elevation of an inclined oven through the retorts partly on line $z-z$ and partly on line $z-u$ Fig. 8. Fig. 7. is a 40 longitudinal sectional elevation of an inclined oven through the flues on line $w-w$ Fig. 8. Fig. 8. is a transverse sectional elevation on line $v-v$ Fig. 6. and Fig. 7. Fig. 9. is a sectional detail of air and combustion 45 chamber and gas conduit D'. Fig. 10. is a detail of gas conduit D'.

The coke oven is built with the ovens or 50 retorts A and the vertical heating flues B between the ovens in the usual way with a combustion chamber C below the latter to which gas and air are supplied.

In the longitudinal combustion chamber C, I place a gas distributing conduit D provided with a number of small perforations d placed

closely together along its upper surface. The perforations d form outlets and burners 55 for the gas. The cross section of the gas conduit D is greater than that of the perforations or outlets d in order to maintain an equal pressure of gas throughout the length of the conduit at each perforation and thereby equalize the pressure of the gas throughout the whole length of the combustion chamber. The gas conduit D is constructed of pipes of earthenware or metal or other material made in lengths with spigot and 60 socket joints which are jointed together and placed in the combustion chamber C from end to end. The combustion chamber C and the air delivery chamber E are built as one cavity separated by the gas conduit D 70 around which through air passages c^2 the air rises to support combustion in the chamber C and vertical flues B.

In a horizontal oven (as in Figs. 1 to 5) the bottom of the combustion chamber C is 75 formed with a number of tiles c placed on ledges c' with an air passage c^2 in the sides of or between every pair of tiles. The tiles c form a partition or division wall between the combustion chamber C and the air delivery flue E beneath it. The earthenware pipes forming the conduit D are D shaped in cross-section and are placed upon the tiles c or the pipes may be formed with ledges 80 at either side to rest upon the projecting 85 bricks c' .

In an inclined oven (as in Figs. 6 to 10.) the bottom of the combustion chamber is formed by the gas conduit D' the pipes forming which are provided with side 90 flanges d' (Figs. 9 and 10.) which rest at intervals upon projecting bricks c' in the side of the chamber. The air delivery chamber E is also constructed of large area in proportion to the air passages or outlets c^2 95 to equalize the pressure of the air escaping through the latter. The air passages c^2 in the top of the air delivery chamber E deliver the heated air at the sides of the gas conduit D in the bottom of the combustion chamber C. If desired air may also 100 be delivered to the gas flue at one end or otherwise to provide a Bunsen flame. Air flues F in which the air is heated are formed in the crowns of the ovens A and of the 105 heating flues B and these serve the double

purpose of heating the air supply and of keeping the crowns of the ovens cool. The oven crowns are built of tiles or bricks G with the flues or passages F through them. The flues under the retorts A are built as one flue or cavity and are divided into four separate flues or passages by means of tiles or thin partitions m m' forming a hot products flue L immediately below the retort 10 base for the heated products of combustion; an air flue M through which the heated air flows in an opposite direction; a second flue L' for hot products leading to the chimney flue R and a second air flue M' the two latter being divided by the thin vertical partitions m' . The air flues F in the crowns of the ovens connect by an external pipe N with the air flues M' alongside the flue L'. The air flue M' at one end connects with the 15 air flue M situated between the hot products flues L and L' beneath the floor of the retort A; and the air flue M connects with the air delivery chamber E beneath the combustion chamber C. By this arrangement 20 each retort A is built or constructed as a separate unit with the side walls resting direct upon the foundations which gives great stability to the structure, and the regenerative heating of the air is obtained 25 without reversing the current by causing the air to flow in close contact with the hot products flues and in a direction contrary 30

to and at the same time parallel to the products of combustion.

What I claim as my invention and desire 35 to protect by Letters Patent is:—

1. In a coke oven the combination with the retorts A and vertical heating flues B of a large cavity beneath the flues B divided by a gas conduit into a combustion chamber 40 C and air delivery chamber E, and a large cavity beneath the retorts A divided by thin tiles m m' into the flues L L' for heated products and flues M M' for air substantially as described. 45

2. In a coke oven the combination with the retorts A and vertical heating flues B of a large cavity beneath the flues B divided by a gas conduit into a combustion chamber C and air delivery chamber E, and a large 50 cavity beneath the retorts A divided by thin tiles m m' into the flues L L' for heated products and flues M M' for air, air passages F in the crown and pipes N to conduct the heated air from the passages F to 55 the flues M' substantially as described.

In testimony whereof I have hereunto set my hand in presence of two subscribing witnesses.

WALTER WINSTANLEY PECK.
